YORK, N. Y., A CORPORATION OF NEW YORK.

TELEPHONE SYSTEM.

1,251,752.

Specification of Letters Patent.

Patented Jan. 1, 1918.

Application filed December 29, 1916. Serial No. 139,525.

To all whom it may concern:

Be it known that we, HENRY P. CLAUSEN and CHARLES L. GOODRUM, citizens of the United States, residing at Mount Vernon, in the county of Westchester and State of New York, and at New York, in the county of New York and State of New York, respectively, have invented certain new and useful Improvements in Telephone Systems, of which the following is a full, clear, concise, and exact description.

This invention relates to telephone switching systems of a type employing automatic switching apparatus in the completion of connections and has for its object in general, the provision of apparatus and circuits for facilitating the rapid hunting over a large number of contacts in the making of connections.

In accordance with the general features of this invention, the terminals over which hunting is to take place are divided into two general groups, and means are provided for automatically transferring the hunting movement of the brushes from one group to the other in case all terminals in the first group to which the brushes have been moved are busy. The apparatus and circuits are so arranged that a plurality of brushes are adapted to simultaneously engage and test separate terminals in the time required to move the brushes between adjacent terminals.

Specifically, the terminals are divided into two groups, each group comprising two sub-groups, and the switch is provided with a set of brushes for each sub-group which are adapted in the movement of the switch to simultaneously engage contacts of their respective sub-groups. Switching mechanism operating in conjunction with the brush moving mechanism is adapted to successively include each set of brushes in the testing circuit for each step or movement of said brushes. Provision is also made whereby, when a set of brushes has been moved into operative relation with one group of terminals by directive impulses, the switch will operate automatically to move said brushes into operative relation with the other group of terminals in case all of the terminals of the first group are busy. This is accomplished through the agency of a test brush

carried by the switch operating in conjunction with the driving mechanism of said switch to advance the brush carrying shaft through a distance less than its normal movement in response to an impulse.

More specifically this invention contemplates the combination, in a selective switch, of means by which groups of trunks may be tested in one operation, and means by which a plurality of separate trunks may be tested at a higher speed than the speed of the switch when the speed of the switch is defined as the number of contacts a brush passes over in a given time.

The drawing represents diagrammatically a calling subscriber's sub-station connected through a line switch (indicated by the broken lines but not shown) to a selector switch embodying this invention.

S' represents a calling subscriber's sub-station; the brushes b^1 , b^2 and b^3 represent brushes of a line switch; and SS represents a selector switch. Let it be assumed that the subscriber at sub-station S', in making a call, removes his receiver from its hook, and in a well-known manner the brushes b^1 , b^2 and b^3 of the line switch are extended to terminals t^1 , t^2 , t^3 of the selector switch SS. A circuit is thereupon established from ground, battery, right-hand winding of relay LR', first position contact and side-switch wiper W', the terminal t' , the brush b' , the telephone line and apparatus of the subscriber's sub-station S', the brush b^2 , the terminal t^2 , the side-switch wiper W^2 , its first position contact, the left-hand winding of line relay LR' to ground. The line relay attracts its armature and establishes a circuit from ground, the armature and alternate contact of relay LR', the winding of the first slow relay 1 to battery and ground.

It should be noted that the system herein disclosed is one in which the idle condition of a selective switch is denoted by a ground potential on the terminals of the circuits, and in the case illustrated, the idle condition of the selector was denoted, before its seizure, by a ground on the terminal t^2 extended from ground, the armature and normal contact of relay LR', the armature and normal contact of relay 1, first position contact and side-switch wiper W^2 to terminal t^2 . Upon the seizure of this selector switch the

ground was removed, as heretofore described, by the energization of relays LR' and 1.

Relay 1 now attracts its armature and 5 prepares a circuit for the primary movement of the selector switch.

When the subscriber at sub-station S' operates his impulse-sender D, a series of interruptions in the line circuit are caused 10 thereby, and result in the intermittent de-energization of relay LR', whereby its armature is caused to vibrate rapidly. Upon the first retraction of this armature a circuit is established from ground, armature and normal 15 contact of relay LR', the armature and alternate contact of relay 1 to a point where the circuit divides, extending in one direction through the primary magnet PM to battery and ground, and in the other direction 20 through the winding of relay 2 to battery and ground. Relay 2 being slow to release is not affected by the intermittent interruptions of this circuit and retains its armatures in their attracted positions until 25 the impulse-sender D has completed its full movement. The primary magnet PM, however, is responsive to the intermittent de-energization of relay LR' and causes its armature to rapidly vibrate, whereby the pawl 30 P is brought into engagement with the ratchet member 3, and causes the rotation of the shaft 4.

It should be noted at this point that the armature of the magnet PM is so adjusted 35 that the pawl P will engage every other tooth of the ratchet member 3, and thereby rotate the shaft two steps in each movement. It should also be noted that the brush 5 secured to the uppermost end of the shaft 4 40 passes over two of the terminals 6 at each step, and comes to rest on a terminal 6 to which a circuit 7 is connected.

Upon the completion of this movement by the impulse transmitter D, and the receipt of 45 the last impulse, the armature of relay LR' is held attracted for a comparatively long period of time and the circuit over which relays 2 and PM were energized is opened at that point.

50 Two sets of brushes B¹ and B² have now been brought into association with a group of terminals including the subgroups G¹ and G², and the switch is made ready for hunting over the terminals in these two subgroups in 55 search of an idle line leading to a second selector switch or a connector switch.

When at first relay 2 was energized, a circuit was established from ground, the contact and left-hand armature of relay 2, winding 60 of escape magnet 16, battery and ground, through which the escape magnet was energized and held energized until after the impulse transmitter D completed its full movement. Now, upon the de-energization of relay 2, this circuit is opened and another cir-

cuit is established from ground, battery, winding of magnet PM, the winding of magnet 8, normal contact and right-hand armature of relay 2, the side-switch wiper W⁴ and its first position contact, the brush 5, the terminal 6, circuit conductor 7, through the off-normal contacts of the switches, the trunks to which terminate in subgroups G¹ and G², in series, to ground, if, as we may assume, all of these switches are busy. Through this circuit then, and before the escape magnet, due to its slow release feature, can retract its armature, the magnets 8 and PM are energized. Magnet 8 attracts its armature and through the extension 9 puts a stop in the path of the armature of magnet PM, whereby the pawl P is allowed to turn the shaft only half as far as in its ordinary movement. In such a manner the sets of brushes B¹ and B² are brought into 85 association with the subgroups of terminals G³ and G⁴.

The escape magnet 16 retracts its armatures, and in so-doing steps the side-switch wipers into the second position. Thereupon a circuit is established from ground, side-switch wiper W⁶, its second position contact, the normal contact and innermost lower armature of slow acting relay 10, the winding of secondary magnet SM to battery and ground. Secondary magnet SM attracts its armature and through the pawl 11 steps the shaft one vertical step, thereby bringing the brushes of the sets B¹ and B² into association, respectively with the terminals of the first trunks in subgroups G³ and G⁴.

If the first terminals of the subgroup G⁴, which are encountered by the brush set B², lead to a selector switch which is idle, ground, by which this idle condition is denoted, will be extended from the test terminal of such set of terminals, through the test brush of the set B², the normal contact and innermost upper armature of the slow-acting relay 10, the side-switch wiper W⁵ and its second position contact, the winding of escape magnet 16, to battery and ground. In this instance the escape magnet is arranged to step the side-switch wipers into their third position upon its energization, and since it is energized through the circuit just described this action will take place. The side-switch wiper W⁶ moving into the third position, breaks the energizing circuit of the magnet SM, whereby this magnet will become de-energized, and the shaft 4 will be held in its elevated position through the agency of pawl 12.

Let it be assumed that the first set of contacts encountered in the subgroup G⁴ lead to a selective switch which is busy. Such condition will be denoted by the absence of ground potential on the test terminal, the escape magnet 16 will not be energized as before described, and a circuit will be estab-

lished from ground, the contacts 13 operated by the armature of the stepping magnet SM, the winding of relay 10, to battery and ground. Relay 10 being slow to act will not 5 attract its armatures until after sufficient time has elapsed for the test heretofore described to take place.

Upon the attraction of its armatures by the relay 10, should the first set of terminals in subgroup G³ lead to an idle selective switch, then a ground, as before described, will be projected over the test terminal of such set of terminals through the test brush of the set B', the alternate contact and innermost upper armature of the relay 10, the side-switch wiper W⁵, and then over the circuit previously described, whereby the side-switch wipers will be moved into the third position. In this case, however, the 15 circuit is established from ground, side-switch wiper W⁶ and its third position contact, the contact and outermost lower armature of the relay 10, the winding of relay 10, to battery and ground. Magnet SM is deenergized as before and the shaft 4 is retained in its elevated position through the pawl 12.

The talking conductors of the lines, however, are now extended through the two outermost upper armatures and alternate contacts of relay 10 to the brushes of the set B', the terminals of the subgroup G³, and then to the seized selected switch. It will be noted that relay 10 is locked in its circuit and will remain so energized until the conclusion of the conversation.

Should the first terminal set in the subgroup G⁴, and the first terminal set of the subgroup G³ have both been found busy, 40 then, upon the energization of relay 10, the circuit for the energization of magnet SM will be opened at the innermost lower armature and normal contact of relay 10, whereby stepping magnet SM is deenergized. In 45 turn, the circuit for magnet 10 is opened at the contacts 13 which, in retracting its armatures, again establishes the circuit for stepping magnet SM, whereupon the shaft 4 is elevated a second step, and the operation 50 of testing, first in the subgroup G⁴, and then in the subgroup G³, is repeated.

Upon completion of the conversation the seized connector switch is released in the well-known manner, with the result that a 55 ground is placed on the test brush of the selector switch SS and is projected over the innermost upper armature of relay 10, the side-switch wiper W⁵ and its third position contact, side-switch wiper W⁶ and its third 60 position contact, the armature and contact of magnet 16, the winding of relay 14 to ground. Through the attraction of its armature by relay 14, the pawls 12 and 15 are withdrawn from their associated ratchet 65 members and the switch is released. A lock-

ing circuit for magnet 14 is established from ground, the off-normal contact ON, the member 15, which serves as an armature of relay 14, its associated contact, winding of relay 14, to battery, and ground, and this 70 circuit is maintained until the switch is fully restored and the contact ON opened.

What is claimed is:

1. In a telephone system, a selective switch, groups of circuits terminating therein, means for testing the busy condition of said circuits by groups, means for moving said switch into a plurality of testing positions, and means for successively testing the busy condition of a plurality of circuits in 75 each of said positions.

2. In a telephone system, a selective switch, groups of circuits terminating therein, and the combination with means for testing the busy condition of said circuits by 80 groups, of means for successively testing the busy condition of said circuits at a higher speed than the speed of said switch.

3. In a telephone system, a selective switch, groups of fixed terminals, circuits 85 connected thereto, brushes arranged in operative relation to said terminals, motive means for said brushes, testing means responsive to a characteristic electrical condition on said terminals indicating an idle 90 condition of said circuits, said testing means being constructed and arranged to operate at a higher speed than the speed of said switch, and means for determining the busy condition of said circuits by groups before 95 100 said brushes are set in motion.

4. In a telephone system, a selective switch, groups of fixed terminals, circuits connected thereto, brushes arranged in operative relation to said terminals, motive 105 means for said brushes, testing means responsive to a characteristic electrical condition on said terminals indicating an idle condition of said circuits, said testing means being constructed and arranged to operate 110 at a higher speed than the speed of said switch.

5. In a telephone system, a selective switch, groups of fixed terminals, circuits connected thereto, brushes arranged in 115 operative relation to said terminals, testing means responsive to a characteristic electrical condition on said terminals indicating an idle condition of said circuits, means for moving said brushes into a plurality of testing positions, and means for successively associating said testing means with a plurality of circuits in each of said positions.

6. In a telephone system, a selective switch, groups of fixed terminals, circuits connected 125 thereto, brushes arranged in operative relation to said terminals, testing means responsive to a characteristic electrical condition on said terminals indicating an idle condition of said circuits, means for moving said 130

- brushes into a plurality of testing positions, means for successively associating said testing means with a plurality of circuits in each of said positions, and means for determining the busy condition of said circuits by groups before said brushes are set in motion.
7. In a telephone system, a selective switch, groups of fixed terminals, circuits connected thereto, means for testing the busy condition of said circuits and groups, means responsive to said testing means for advancing said brushes to other groups of said terminals, means for moving said brushes into a plurality of testing positions, and means for successively testing the busy condition of a plurality of said circuits in each of said positions.
8. In a telephone system, a selective switch, banks of fixed terminals, circuits connected thereto, means for testing said circuits in groups, sets of brushes arranged in operative relation to said terminals, actuating means for said brushes, and means for testing a plurality of said circuits individually during each movement of said brushes.
9. In a telephone system, a selective switch, banks of fixed terminals, circuits connected thereto, sets of brushes arranged in operative relation to said terminals, an auxiliary set of terminals, an auxiliary brush arranged in operative relation to said auxiliary terminals, means including said auxiliary terminals and said auxiliary brush for testing said circuits in groups, actuating means for said brushes, and means including said terminals and said brushes for testing a plurality of said circuits individually during each movement of said brushes.
10. In a telephone system, a selective switch, banks of fixed terminals, circuits connected thereto, means for testing said circuits in groups, sets of brushes arranged in operative relation to said terminals, means responsive to said group testing means for advancing said brushes into association with other banks of said terminals, actuating means for said brushes and means for testing a plurality of said circuits individually during each movement of said brushes.
11. In a telephone system, a selective switch, banks of fixed terminals, circuits connected thereto, means for testing said circuits in groups, sets of brushes arranged in operative relation to said terminals, means responsive to said group testing means for advancing said brushes into association with other banks of said terminals, actuating means for said brushes, and means for testing a plurality of said circuits individually and in succession during each movement of said brushes.
12. In a telephone system, a selective switch, banks of fixed terminals, circuits connected thereto, sets of brushes arranged in operative relation to said terminals, actuating means for said brushes, testing means responsive to an electrical condition established through the busy condition of all of the circuits terminating in one bank of said terminals for controlling said actuating means, and means for testing in succession a plurality of said circuits in each operation of said actuating means.
13. In a telephone system, a selective switch, banks of terminals sub-divided into groups and subgroups, circuits connected thereto, sets of brushes arranged in operative relation to said terminals in each of said banks of terminals, said sets of brushes being equal in number to the number of subgroups in each group of said terminals, actuating means for said brushes, testing means responsive to the busy condition of all of the circuits terminating in a group of said terminals for advancing said brushes into association with another group of said terminals, and means for successively testing an individual circuit in each subgroup of the group with which said brushes have been associated during each movement of said brushes.
14. In a telephone switching system, a switch including a plurality of brushes, a group of circuit terminals, means for simultaneously moving said brushes over said terminals, a test circuit, and means for successively including said brushes separately in said test circuit during the time required to move said brushes between adjacent terminals.
15. In a telephone switching system, a switch including a plurality of brushes, a group of circuit terminals, motive means for simultaneously moving said brushes over said terminals, a test circuit, and switching means coöperating with said motive means for separately and successively including said brushes in said test circuit during the time required to move said brushes between adjacent terminals.
16. In a telephone switching system, a switch including a plurality of brushes, a group of circuit terminals, step-by-step means for simultaneously moving said brushes over said terminals, a test circuit, and means for separately and successively including said brushes in said test circuit during one step of said step-by-step means.
17. In a telephone switching system, a switch including a plurality of brushes, a group of circuit terminals, step-by-step means for simultaneously moving said brushes over said terminals, a test circuit, and switching means coöperating with said step-by-step means for separately and successively including said brushes in said test circuit during a single stepping movement of said switch.

18. In a telephone switching system, a switch including a plurality of brushes, groups of circuit terminals, means for causing said brushes to automatically move from one group to another in case all of the terminals in the one group test busy, means for simultaneously moving the brushes over the terminals of a group, and means for testing all of the terminals with which said brushes are engaged in any position of the switch.

19. In a telephone switching system, a switch including a plurality of brushes, groups of circuit terminals, means responsive to directive impulses to move said brushes into position to engage terminals of one of

said groups, means operating automatically in case all terminals of the first group are busy to cause said brushes to move into position to engage terminals of another group, means for simultaneously moving said 20 brushes over the terminals of a group, and means for testing all of the terminals with which said brushes are engaged in any position of the switch.

In witness whereof, we hereunto subscribe 25 our names this 28th day of December A. D., 1916.

HENRY P. CLAUSEN.
CHARLES L. GOODRUM.
